UNITED STATES PATENT OFFICE

ARTHUR E. JONES, OF TONAWANDA, NEW YORK, ASSIGNOR TO HENRY WEIS MANUFACTURING COMPANY, INC., A CORPORATION OF INDIANA

CONSTRUCTION UNIT

Application filed November 9, 1928. Serial No. 318,141.

This invention relates to fabricated sheet metal construction units, and aims to provide a partition or panel construction in which the elements thereof may be easily and readily assembled and the resulting units will be rigid and will have a neat appearance.

The nature of the invention may be readily understood by reference to one illustrative construction embodying the invention and 10 shown in the accompanying drawing.

In said drawing:

Fig. 1 is an elevation of a construction unit, a portion of which has been broken away to reveal details on the interior of the unit.

15 Fig. 2 is a cross section of the unit (on an enlarged scale relative to that of Fig. 1) taken on a plane perpendicular to the face of the unit and parallel to one of its edges.

Fig. 3 is a perspective view (also enlarged 20 as compared to the scale of Fig. 1) of a corner of the unit with the edge strip removed.

Fig. 4 is an elevation of a pair of adjoining edge strips, separated slightly so as to show the mitered ends.

25 Fig. 5 is a development or pattern of the corner of one of the panel sheets as it is cut or blanked out and before the metal has been bent into the form shown in Fig. 3.

Fig. 6 is a perspective view of a door made 30 from one of the illustrative units.

The illustrative unit comprises a pair of marginally flanged panels 10 and 11, advantageously made of sheet metal, connected together at their edges by connecting means 35 which provide a rigid, double-walled unit. In the present case the marginal flanges 12 of the panels are provided with means in the form of inwardly turned extremities 13 which cooperate with the connecting elements 14 to hold the sheet metal panels in assembled relation.

The connecting element 14 is in this instance in the form of an edge strip whose head 15 lies over the joint between the panels and 40 whose shank 16 extends between the marginal flanges 12 and is provided with means, in the form of hooks 17 having inclined cam faces 18, for engaging the flange extremities 13. In the present case the head 15 of the connecting 45 element is arched and made resilient so as to

be capable of drawing the hooks 17 tightly against the flange extremities 13, thereby holding the panels together under a resilient tension and removing all looseness and play between the various elements of the unit. To 55 secure this result the parts must be proportioned so that the arched head is slightly flattened when applied to set up the necessary tension. In this instance the inclined surfaces 18 on the hooks 17 exert a cam action on the 60 extremities 13 by means of which the panels are drawn tightly together and thus held under the resilient pressure provided by the arched head 15.

The connecting element may advantageously 65 be made of sheet metal folded into the form indicated in Fig. 2. The ends of the connecting element are beveled (in this case at angles of 45°) so as to form mitered joints at the corners of the unit.

70 The flanges on panels 10 and 11 are advantageously made integral therewith by forming the panels of sheet metal which is blanked out in flat condition and later bent at the margins to provide the flanges 12 and their extremities 13. Fig. 5 shows a development or pattern of a portion of a panel blank showing the outline of the blank at the corner of the panel and (in dot and dash lines) the lines along which the metal is bent to form the marginal flanges 12 and their extremities 13. 75 The cut-away portions at the corner of the blank provide the open spaces 19 at each corner of the unit desirable for the insertion or application of the edge or connecting strip. 80 In assembling a unit, a pair of panels is arranged as indicated in Fig. 3 and marginal strips, successively supplied by inserting their ends into the spaces 19, and sliding the strip longitudinally of the panels into position. The ends of the extremities 13 are advantageously beveled as indicated at 20 so as to wedge into the space between the hooks 17 and the head of the edge strip. Thus the head 15 is automatically flattened or placed under 85 tension when the strip is forced against and over the beveled ends 20 of the extremities 13.

In order to apply the last or fourth edge strip it is desirable either to cut away or slot 90 an adjacent edge strip to provide a space for

inserting the fourth strip. This is most conveniently effected by cutting away a portion of that edge strip which is in a concealed position. For example in employing the unit 5 as a door panel, the top and bottom edge strips are advantageously cut away to accommodate the hinge fittings 21 (Fig. 6). In such a construction, therefore, the top and bottom edge strips both provide a space for 10 the insertion of the fourth edge strip. If the hinge fittings be applied on the inner edge of a door instead of at the top or bottom, the edge strip may be cut away or severed at the point of application of the hinge fittings, 15 thereby again providing means for inserting the fourth or last edge strip. Where the unit is used as a partition member, the side edges of the unit are usually inserted in recesses in a post or the like which would serve to conceal a cut-away portion of an edge strip. Even if all four edges of the panel were exposed, it would be possible to cut away a bottom edge strip because that would not be visible. It is apparent from the foregoing 20 that all visible portions of the unit will present a smooth surface and that the edge strips will abut in a neatly mitered joint. This joint is advantageously welded, thereby removing all possibility of such slight relative 25 movement between the edge strips as might break enamel or paint at the mitered corner of the edge strips.

In the present case the unit is advantageously provided with a self-supporting filler 30 in the form of a plurality of thick fiber sheets 22 which are cemented together and cemented on outer faces 23 to the panels. Thus the unit is given a solid or substantial quality not possessed by a unit with a hollow or empty 35 interior. The fiber sheets 23 may advantageously be faced corrugated board of common construction.

Obviously the invention is not limited to the details of the illustrative construction 40 since these may be variously modified. Moreover, it is not indispensable that all features of the invention be used conjointly since various features may be employed in different combinations and sub-combinations.

50 Having described one embodiment of my invention, I claim:

1. A fabricated building unit comprising in combination a pair of marginally flanged panels arranged with said flanges in register, the extremities of said flanges being formed to project inwardly into the space between said panels, and a metal joining strip having a shank extending between and engaging said flange extremities and a head engaging 55 said registering flanges and cooperating with the shank thereof to hold said panels together.

2. A fabricated building unit comprising in combination a pair of marginally flanged 60 panels arranged with said flanges in register,

the extremities of said flanges being formed to project inwardly into the space between said panels, and a metal joining strip having a shank extending between said flange extremities and provided with hook means for 70 hooking around said extremities, said strip having a head engaging said registering flanges and cooperating with said hook means to hold said panels together.

3. A fabricated building unit comprising 75 in combination a pair of marginally flanged panels arranged with said flanges in register, the extremities of said flanges being formed to project inwardly into the space between said panels, and a metal joining strip 80 having a shank extending between said flange extremities and provided with hook means for hooking around said extremities, said strip having a resilient, arched head covering the joint between and resiliently pressing 85 against said flanges to cause said hook means to draw said flange extremities together and thereby to join said panels together and to remove any looseness between said panels.

4. A fabricated building unit comprising 90 in combination a pair of marginally flanged panels arranged with said flanges in register, the extremities of said flanges being formed to project inwardly into the space between said panels, and a metal strip having a resili- 95 ent head engaging the respective registering flanges and having means for engaging said flange extremities, said head being distorted upon application thereof to the panels whereby to exert a resilient pressure for holding 100 said panels tightly together.

5. A fabricated building unit comprising in combination a pair of marginally flanged panels arranged with said flanges in register, the extremities of said flanges being formed 105 to project inwardly into the space between said panels, and a resilient metal strip having means for engaging said flange extremities, said strip being distorted upon application thereof to said panels whereby to draw said panels together with a resilient pressure. 110

6. A fabricated building unit comprising in combination a pair of marginally flanged panels arranged with said flanges in register, the extremities of said flanges being formed to project inwardly into the space between said panels, a metal joining strip having a shank extending between said flange extremities and provided with hook means for hooking around said extremities, said strip having a resilient, arched head covering the joint between and resiliently pressing against said flanges to cause said hook means to draw said flange extremities together and thereby to join said panels together and to remove any looseness between said panels, and a self-supporting filler occupying the space between said panels and to which said panels are cemented. 120

7. A fabricated building unit comprising in

combination a pair of panels having their margins in register and provided with connecting flanges, a joining strip having a head covering the joint between the panels and 5 having a shank engaging said connecting flanges to hold the same together, said flanges being beveled at their ends so as to wedge between the head and shank of said joining strip, whereby the panels are connected firmly and play between them is eliminated.

8. A fabricated metal partition construction comprising in combination a pair of sheet metal panels arranged with their margins in register, and joining means including a 15 metal strip covering the joint between said margins and cooperating to secure said panels together, said strip being distorted in its application to said panels to exert resilient pressure in planes parallel to said panels to 20 remove relative movement between the panels and between the panels and said strip.

9. A fabricated metal partition construction comprising in combination a pair of marginally flanged sheet metal panels arranged with their flanges in register, and joining means including a metal strip located at the joint between said flanges, said strip being distorted in application to said panels and constructed and arranged to exert a resilient pressure in planes parallel to 30 said panels to prevent relative longitudinal shifting thereof.

10. A fabricated metal partition construction comprising in combination a pair of parallel, marginally flanged sheet metal panels arranged with their flanges in register; and joining means including a metal strip on the exterior of said panels and covering the joint between said flanges and a portion extending into the interior of said panels and connected with said flanges on the interior of 40 said panels to secure said panels together.

11. A fabricated metal partition construction comprising in combination a pair of parallel, marginally flanged sheet metal panels arranged with their flanges in register; joining means including a metal strip covering the joint between said flanges and cooperating to secure said panels together, said strip 50 having a portion extending between said flanges into the interior of said panels and connected therewith in said interior.

12. A fabricated building unit comprising in combination a pair of parallel, marginally flanged panels arranged with said flanges in register; the extremities of said flanges being formed to project inwardly into the space between said panels; and a joining strip covering the joint between said panels and 60 engaging said extremities in the interior of said panels and cooperating to hold said panels together.

13. A fabricated building unit comprising in combination a pair of parallel, marginally flanged panels arranged with said flanges in

register; the extremities of said flanges being formed to project inwardly into the space between said panels; and an exteriorly applied resilient metal joining strip having means extending into the interior of said panels for 70 engaging said extremities with a resilient pressure to hold said panels together.

14. A joining strip for connecting together panels to form a construction unit formed from a strip of sheet metal having 75 the side margins doubled under the central portion to form an arched head, the extremities of said side portion being bent at an angle to the head and brought together to form a shank and the edges thereof being 80 bent over to form hooks.

15. A fabricated metal building unit comprising in combination a pair of opposite, parallel, marginally flanged sheet metal panels having their flanges bent substantially at 85 right angles to the panel and arranged in register with those of the opposite panel; joining means including an exterior metal strip covering the joint between said flanges and cooperating to secure said panels together, said flanges engaging and abutting said strip to hold said panels spaced apart.

16. A fabricated building unit comprising in combination a pair of opposite, parallel, marginally flanged panels having said 90 flanges formed substantially at right angles to the panels and arranged in registry with those of the opposite panel; the extremities of said flanges being formed to project inwardly into the space between said panels; and a joining strip fitting over said extremities and cooperating therewith to hold said panels together.

17. A fabricated building unit comprising 100 in combination a pair of opposite, parallel, marginally flanged sheet metal panels having said flanges bent substantially at right angles to the panels and arranged in register with those of the opposite panel; said flanges having their extremities bent to project inwardly into the space between said panels; and an elongated metal joining strip bent to have its edges brought into opposite relationship and being wedged over said extremities to hold said panels tightly together.

18. A double walled panel structure of the character described comprising in combination a pair of opposite, parallel, marginally flanged imperforate metal panel sheets arranged with their flanges in register and having a fixed relation to each other; said panel sheets providing double walls throughout said panel structure, joining means connecting said flanges and including a metal strip straddling the joint between said flanges, the metal of said strip being distortable to exert a resilient pressure against said panels to resist relative longitudinal shifting thereof; and filling material be-

tween said panel sheets to eliminate the drum effect of the metal panel sheets.

19. An elongated sheet metal joining strip for connecting together panels to form a construction unit comprising in combination a curved resilient head adapted to be slightly flattened upon application of the strip, and a shank adapted to pass between the panels and to extend beyond the opposite faces of said panels, and panel engaging means at the extremity of said shank adapted to extend beyond said opposite faces of said panels and to engage said panels to hold the latter together.

15 In testimony whereof, I have signed my name to this specification.

ARTHUR E. JONES.
